UNITED STATES PATENT OFFICE.

NELSON H. RAYMOND, OF BROOKLYN, AND JOSEPH C. VETTER, OF CONEY ISLAND, NEW YORK, ASSIGNORS TO ALICE C. PATTERSON, OF NEW YORK, N. Y.

ELECTROTHERAPEUTIC APPARATUS.

No. 872,148.

Specification of Letters Patent.

Patented Nov. 26, 1907.

Application filed August 24, 1905. Serial No. 275,653.

To all whom it may concern:

Be it known that we, NELSON H. RAYMOND and JOSEPH C. VETTER, citizens of the United States, residing at Brooklyn, New York, and Coney Island, New York, respectively, have invented certain new and useful Improvements in Electrotherapeutic Apparatus, of which the following is a full, clear and exact description.

10 Our invention relates to electro therapeutic apparatus, and particularly to implements intended to be used by hand.

The object of the invention is to provide a simple and reliable apparatus the parts of 15 which may be held in the two hands, and applied to such parts of the body as may be desired, while the current is controlled by means operable by the thumbs of each hand. By this we do not wish it inferred that the 20 apparatus cannot be used in any other way. It is, however, the most convenient.

The invention consists in improvements 25 the principles of which are illustrated in the accompanying drawings. It contemplates an induction apparatus with a battery and coil.

The apparatus comprises two members, each of which carries a suitable electrode for applying the secondary or induced current. 30 One member contains the battery and has a controller therefor, while the other member contains the induction apparatus and has a regulator therefor.

Figure 1 is a view of the apparatus embodying our invention, parts of the same being broken away to show the interior construction. Fig. 2 is a fragmentary longitudinal sectional view of the part of the apparatus for turning on and off the primary current. Fig. 3 is a cross sectional view of the apparatus for controlling the secondary current, the same being taken on the plane of the line X—X Fig. 1. Fig. 4 is a detail view of the cross bar 12. Fig. 5 is a view showing 45 in diagram the wiring and electrical connections in both members.

1 indicates the casing of the battery member, preferably of insulating material. 2 represents a suitable form of dry battery 50 contained therein. 3 represents one terminal of the battery. 4 is a screw taking into the electrode socket 5, and connecting it to the screw-threaded cap 6. 7 is a threaded ring member carried by the casing 1, and to 55 which is connected the wire 8. 9 is a sta-

tionary contact member to which wire 8 is connected. 10 is a plate or base removably mounted in the case 1 and affording an abutment for the spring 11, which affords electrical connection with the other terminal—60 the bottom of the cell 2. 12 is a cross bar of insulating material, such as ebonite through which the conducting wires pass. 13 and 14 are screw posts projecting from the plate 10 and to which electrical connection is made 65 beneath the bar 12. The spring 11 is electrically connected to post 13. Post 14 is electrically connected by wire 15 to the longitudinally movable contact member 16. Contact is made between members 16 and 9 70 by depressing the member 16 for momentary contact, or sliding it longitudinally beneath the lip of the contact 9 for a prolonged contact, for instance, as set forth in U. S. Letters Patent No. 780,523. To operate the opening and closing of the primary circuit, it is simply necessary to hold the case 1 in the hand, and apply the thumb to the contact member 16.

The other member, the "induction member", of the apparatus is shown at the left in the drawing. 17 represents the casing which similarly to casing 1, is formed of insulating material. 18 represents the induction coil, containing the primary and secondary 85 windings P and S. 19 and 20 represent the two heads of the spool of the induction member. 21 and 22 are rods rigidly connecting the heads 19 and 20 and serving as part of the electrical circuit, the head 20 being removably secured in the casing. The two wires from the battery member pass through the cross bar 23 and are secured to the ends of the rods. 24 is a screw-threaded cap having a central opening for the wires or conductor 90 cable. 25 is a sleeve or tube longitudinally movable on the coil 18 for varying the field. 26 is a scale member carried by the adjusting sleeve 25 having a grooved portion guided by the rod 27. 28 is a pinion carried by the casing projecting slightly outwardly therefrom, and engaging on the interior with a rack 29, movable with the scale and adjusting sleeve. The numbers on the scale are visible through a suitable opening. 30 represents the armature member for the primary coil. 31 is the adjustable contact screw, having a platinum point. The primary circuit passes through the two rods 21 and 22, through the armature 105 30 and contact 31, so that when the current 110

is turned on in the battery member, it is repeatedly interrupted by the action of the armature member, thus causing repeated induced currents in the secondary circuit.

5 32 is a spring arm, which, contacting with the screw 33, affords electrical connection to the terminal socket 34 when the screw cap 35 is in place.

36 and 37 represent suitable electrodes for 10 applying the instrument to the body. The secondary circuit when the instrument is applied, passes from the electrode 37, through socket 5, cap 6, ring 7, wire 8, contacts 9 and 16, wire 15, then through one of the wires 15 connecting the battery member to the induction member, thence through one of the rods 21 or 22 to the spring contact 32, screw 33, socket 34 and electrode 36, and then through such parts of the body as intervene between 20 the electrodes 36 and 37.

As the induction member is grasped in the hand, the current may be regulated by a simple movement of the thumb upon the pinion 28. By this construction, the control of the 25 primary circuit and the regulation of the secondary circuit may be accomplished by similar movement, as the two members of the instrument are held in the two hands of the operator. No confusion can thus arise, and the 30 primary current may be instantly turned on or off as desired, or the secondary current

may be instantly increased or diminished as desired, at any time.

The advantages of such an apparatus, besides those above pointed out, will be apparent to those acquainted with the operation and application of electro therapeutic apparatus.

What we claim is:

1. As an article of manufacture, a casing, a 40 removable cap at one end thereof, a battery contained within said casing, a base plate, a spring interposed between the base plate and said battery, binding posts carried by said plate, a second cap removably secured to 45 said casing and having a perforation for the passage of electrical conductors.

2. In a device of the character described, a combination of a casing, a battery member contained therein, a longitudinally movable 50 contact member carried by said casing for controlling the battery current, a plate mounted in said casing, binding post carried thereby, and a removable cap carried by said casing having an opening for the passage of 55 electrical conductors.

NELSON H. RAYMOND.
